UNITED STATES PATENT OFFICE.

ALBERT E. MOORHEAD, OF SAN FRANCISCO, CALIFORNIA, ASSIGNOR TO AMERICAN ROTARY VALVE COMPANY, OF CHICAGO, ILLINOIS, A CORPORATION OF ILLINOIS.

PNEUMATIC SCRUBBING APPLIANCE.

1,042,713.

Specification of Letters Patent.

Patented Oct. 29, 1912.

Application filed October 28, 1908, Serial No. 459,950. Renewed July 28, 1911. Serial No. 640,970.

To all whom it may concern:

Be it known that I, ALBERT E. MOORHEAD, a citizen of the United States, residing at San Francisco, in the county of San Francisco and State of California, have invented new and useful Improvements in Pneumatic Scrubbing Appliances, of which the following is a specification.

The present invention relates to a scrubbing appliance adapted to be used with pneumatic cleansing apparatus in general use in office buildings and the like.

The object of the invention is to provide a device by means of which water, either plain or mixed with a disinfectant liquid, can be discharged over the floor to be cleaned, the floor scrubbed with the water, and the dirty water returned to the tank of the pneumatic apparatus.

20 In the accompanying drawing, Figure 1 is a perspective view of the apparatus; Fig. 2 is a longitudinal section of the scrubber proper; Fig. 3 is a cross section on the line 3-3 of Fig. 2.

25 Referring to the drawings illustrating in detail one of the preferred forms of my invention, 1 indicates an upper casing section formed with a conduit 2 extending upward and then in a longitudinal direction 30 and connected at its outer end with a swiveling union 3, which is secured thereto by a screw bolt 4, so as to be able to turn upon said bolt as an axis and within the beveled outer mouth 5 of said conduit. Said union 35 is secured to a hollow handle 6, which is connected in the usual manner at the outer end to a flexible hose 7 adapted to be connected with suitable pipes leading to the pneumatic cleansing apparatus, so that said 40 handle forms also a suction conduit for drawing up the dirty scrub water. This movable connection between the hollow handle and the conduit 2 permits of varying the angle of inclination of the handle to the 45 floor while the brush is moved thereover, while at the same time maintaining a substantially tight joint to preserve the efficiency of the suction. The upper section 1 of the casing is substantially in the form of 50 a rectangular box closed at the top, sides, and ends, but open at the bottom, and within a downwardly extending flange 8 of said casing section is secured by screws 9 the back 10 of a brush, said back thus forming 55 the detachable bottom or lower section of

the casing in which back are secured at suitable intervals tufts 11 of bristles, and, alternating with said bristles, flexible rubber tubes 12. The upper ends of said tubes may be secured in any suitable manner to said back. Said tubes depend to within a short distance of the bottom of the bristles and are adapted to contact with the water upon the floor, and thus by the suction created by the pneumatic cleansing apparatus, the water is drawn up into the casing section 1 through the conduit 2, the handle 6 and the hose 7 to the tank of the pneumatic apparatus.

A rubber tube 14 is secured entirely 70 around the side of the casing section 1 to protect the furniture or walls of the building from contact with said casing.

Formed in the top of the casing is a transverse water conduit 15 having an obliquely 75 directed inlet 16 connected with a pipe 17 which pipe 17 is likewise connected by a flexible hose 18 with a water pipe in the building. Said pipe 17 and handle 6 are provided with adjacent valves 19, 20, convenient for use by the operator, so that the water and suction can be controlled as desired. Said transverse water conduit 15 leads to passages 21 formed in the casing, and extending longitudinally in the sides 80 thereof, there being formed in said casing, beneath each passage, a number of small apertures 22 through which the water is discharged upon the floor.

The mode of operation will be readily 90 understood from the foregoing description. The operator by turning the valve 19 in the water tube can permit the desired quantity of water to flow upon the floor, and then, either when said water is being slowly discharged, or after the same has been shut off, he can scrub the floor with the water thereon, either before, or while, applying the suction, which is controlled by means of the valve 20. When the valve is opened to 100 create a suction to the pneumatic cleansing apparatus the scrub water is drawn up through the rubber tubes and conveyed by the hollow handle 6 to the tank of pneumatic cleansing apparatus, whence it may be 105 discharged into the sewer.

One of the important advantages of this invention is that, after scrubbing, the vacuum by the suction tends to dry the floor 110 very quickly.

While I have shown and described herein certain mechanical details of construction which embody one preferred form of my invention illustrated, it will, of course, be understood that these may be changed and variously modified without departing from the spirit of my invention, and I do not desire to be limited to the construction and arrangement herein shown except as pointed out in the appended claims.

I claim:

1. In an apparatus of the character described, a casing provided with an inlet chamber and with a water chamber having openings adapted for the passage of water therefrom, a hollow handle connected to said casing and constituting a conduit opening into said inlet chamber, means connecting said hollow handle with a device for producing a vacuum therein, scrubbing devices carried by said casing, flexible tubes carried by said casing, said tubes opening at their upper ends into said inlet chamber, and having their lower ends substantially in the contact plane of said scrubbing devices, means for supplying water to the water chamber of said casing, and independent means carried by said handle for controlling said water supply and for controlling the vacuum produced in said inlet chamber.
2. In an apparatus of the character described, a casing provided with an inlet chamber and with water passages located at the lateral edges of said inlet chamber, said water passages being provided with openings for the discharge of water, a hollow handle connected to said casing, and constituting a conduit opening into said inlet chamber, means connecting said hollow handle with a device for producing a vacuum therein, scrubbing devices carried by said casing, flexible tubes carried by said casing and having their lower ends substantially in the contact plane of said scrubbing devices, means for supplying water to said water passages, and independent means carried by said handle for controlling said water supply and for controlling the vacuum produced in said inlet chamber.
3. In an apparatus of the character described, a casing, scrubbing devices secured thereto, said casing being provided with a water chamber having openings for the discharge of water therefrom, means for sup-

plying water to said water conduits, a hollow handle, a movable connection between said hollow handle and casing, and flexible tubes carried by said casing, depending to a depth approximating that of the bottom of the scrubbing devices, said casing having a suction conduit connected with said tubes whereby the scrubbing water may be drawn up through said tubes, substantially as described.

4. In an apparatus of the character described, a hollow casing, scrubbing devices secured thereto, said casing being formed with a water conduit and a passage therefrom for discharging the water upon the floor, a tube connected to said casing for supplying water to said conduit, a handle, flexible tubes carried by said casing and depending to a depth approximating that of the bottom of the scrubbing device, said casing having a suction conduit connected with said flexible tubes whereby the scrubbing water may be drawn up through said flexible tubes and a movable connection between said handle and casing.

5. In an appliance of the character described, the combination of a box-like casing section open at the bottom and closed at the sides and ends, a brush back detachably secured in said casing, and forming the bottom thereof, flexible tubes having their upper ends secured in said back, and extending to substantially the same depth as the brush bristles, said casing being in communication with the upper ends of said flexible tubes, and formed with a conduit leading therefrom, a union connected to said conduit, a handle connected to said union, a valve in said handle, said casing having a water conduit and longitudinal passages connected to said water conduit, and having openings leading downward from said passages, and adapted to discharge the water upon the floor, a tube connected with said water conduit, and a valve in said tube, substantially as described.

In testimony whereof I have hereunto set my hand in the presence of two subscribing witnesses.

ALBERT E. MOORHEAD.
